Primary Examiner—Cathron C. Brooks*Assistant Examiner*—Kelley A. Donnelly(74) *Attorney, Agent, or Firm*—Oblon, Spivak, McClelland, Maier & Neustadt, P.C.(57) **CLAIM**

The ornamental design for an electronic gate, as shown and described.

DESCRIPTION

FIG. 1 is a right side, front perspective view of an electronic gate, showing our design;

FIG. 2 is an additional front and right side perspective view thereof;

FIG. 3 is a top, front and right side perspective view thereof;

FIG. 4 is a right side elevational view thereof;

FIG. 5 is a front and left side perspective view thereof;

FIG. 6 is an enlarged top and right side perspective view of a portion thereof, shown separately for completion of illustration; and,

FIG. 7 is an enlarged perspective view of the circled portion shown in FIG. 4, shown separately for completeness of illustration.

1 Claim, 7 Drawing Sheets---
